UNITED STATES PATENT OFFICE.

ISAAC MAYER, OF NEW YORK, N. Y.

DESIGN FOR A THERMOMETER-FRAME.

SPECIFICATION forming part of Design No. 34,894, dated August 6, 1901.

Application filed June 26, 1901. Serial No. 66,164. Term of patent 7 years.

To all whom it may concern:

Be it known that I, ISAAC MAYER, a citizen of the United States, residing at the city of New York, in the borough of Manhattan and State of New York, have invented and produced a new and original Design for Thermometer-Frames, of which the following is a full, clear, and exact description.

My new and original design for thermometer-frames is illustrated in the accompanying drawing, in which the figure is a front elevation of a thermometer-frame, showing my new design.

The leading or material feature of my design consists of the oblong plane surface A, embraced by a scroll a, made up of compound curved and spiral lines. This scroll extends around all four sides of the oblong surface

and on the lower side is added to by a representation of an opening flower b', the petals 20 appearing slightly separated.

The front-and back faces of the design are the same, the thermometer-scale being marked on the oblong surface on each side.

Having described my invention, what I 25 claim as new, and desire to secure by Letters Patent, is—

The design for a thermometer-frame as herein shown and described.

In witness whereof I subscribe my signature in presence of two witnesses.

ISAAC MAYER.
